UNITED STATES PATENT OFFICE

135,283

DESIGN FOR A BATHTUB

Arthur J. Hunting, Eureka, Calif.

Application January 2, 1943, Serial No. 109,192

Term of patent 7 years

To all whom it may concern:

Be it known that I, Arthur J. Hunting, a citizen of the United States and a resident of Eureka, in the county of Humboldt and State of California, have invented a new, original, and ornamental Design for a Bathtub, of which the following is a specification, reference being had to the accompanying drawing, forming part thereof.

The single figure is a perspective view of a bathtub showing my new design.

I claim:

The ornamental design for a bathtub, as shown.

ARTHUR J. HUNTING.
